US00D570800S

(12) **United States Design Patent** (10) Patent No.: **US D570,800 S**
Chen et al. (45) Date of Patent: **** Jun. 10, 2008**

(54) **ISM-BAND PRINTED ANTENNA FOR A PORTION OF A CIRCUIT BOARD**

(75) Inventors: **Hui-Mei Chen**, Tainan County (TW); **Wei-Hsiu Hsu**, Taipei County (TW); **Huan-Ping Su**, Hsinchu (TW); **Chien-Hsin Su**, Hsinchu (TW)

(73) Assignee: **Uniband Electronic Corp.** (TW)

(**) Term: **14 Years**

(21) Appl. No.: **29/250,640**

(22) Filed: **Nov. 27, 2006**

(51) LOC (8) Cl. **13-03**

(52) U.S. Cl. **D13/182**

(58) Field of Classification Search .... D13/182; D14/230; 343/700 MS, 795, 895

Primary Examiner—Selina Sikder

(57) **CLAIM**

The ornamental design for an ISM-band printed antenna for a portion of a circuit board, as shown and described.

DESCRIPTION

The single FIGURE is a front view of an ISM-band printed antenna for a portion of a circuit board showing the new design. The broken line drawing of an undefined portion of a circuit board is for illustrative purposes only and forms no part of the claimed design.
